(57) **CLAIM**

We claim the ornamental design for a light-emitting diode (LED) luminaire assembly, as substantially shown and described.

DESCRIPTION

FIGS. 1-42 are various views of a light-emitting diode (LED) luminaire assembly in accordance with the present design.

FIG. 1 is a perspective view of a light-emitting diode (LED) luminaire assembly in accordance with a first embodiment of the present design. The broken lines depict portions of the light-emitting diode (LED) luminaire assembly that form no part of the claimed design.

FIG. 2 is a top view of the light-emitting diode (LED) luminaire assembly shown in FIG. 1.
